C. F. JENSEN

LUBRICATOR PUMP

Filed Dec. 2, 1924

INVENTOR.
CARL F. JENSEN
BY *S. H. Baddock*
ATTORNEY.

UNITED STATES PATENT OFFICE.

CARL F. JENSEN, OF BRIDGEPORT, CONNECTICUT.

LUBRICATOR PUMP.

Application filed December 2, 1924. Serial No. 753,503.

To all whom it may concern:

Be it known that CARL F. JENSEN, a citizen of the United States, and resident of Bridgeport, in the county of Fairfield and State of Connecticut, has invented certain new and useful Improvements in Lubricator Pumps, of which the following is a specification.

This invention relates to a lubricator pump, and the object of the invention is to provide a simple and improved selective lubricator pump having means for measuring a "shot" of lubricant and for forcing said "shot" to one of a plurality of bearings or the like to be lubricated.

With the above object in view, as well as others which will appear as the specification proceeds, the invention comprises the construction, arrangement and combination of parts as now to be fully described and as hereinafter to be specifically claimed, it being understood that the disclosure herein is merely illustrative of principle and meant in no way in a limiting sense, changes in details of construction and arrangement of parts being permissible so long as within the spirit of the invention and the scope of the appended claims.

In the accompanying drawing forming a part of this specification,

Fig. 1 is a top plan view of a lubricator pump in which the features of the invention are incorporated;

Fig. 2 is a sectional view on line 2—2 in Fig. 1; and

Fig. 3 is a sectional view on line 3—3 in Fig. 2.

With respect to the drawing, 10 represents a lubricant reservoir with cover 11 removably attached as by screws 12, and 13 denotes a filling opening with threaded and ported plug 14 or ordinary construction.

The lower portion of the reservoir has a well or cavity 15 and adjacent the cavity there is a thickened portion or web 16 having a plurality of ports 17 leading from the well or cavity 15 to threaded openings 18 adapted to receive piping 19 leading to bearings or the like.

Numeral 20 represents an axially rotatable cylinder mounted in the cover 11 as at 21 and having its lower end extending into the well or cavity 15. A lower portion of the cylinder 20 includes a measuring chamber 22 in which a piston or plunger 23 is adapted to be reciprocatable, the piston or

plunger being operable by means of a shaft 24 connected to it and slidably arranged in a longitudinal opening through the cylinder 20. A handle 25 upon the shaft 24 is for actuating the piston.

The measuring chamber 22 of the cylinder 20 terminates at its lower end in a spring-valve-receiving chamber 25 of slightly greater diameter than the measuring chamber to provide a seat 27 at the base of the measuring chamber to receive a spring valve 28 held to said seat 27 as by means of the coil spring 29 the lower end of which is supported in any convenient manner, as 60 by the washer 30 secured at the lower end of the chamber 25, the washer 30 as disclosed resting upon a portion of the base of the well or cavity 15.

The spring valve 28 has an opening 31 arranged through it preferably at its center, and a ball valve 32 within the measuring chamber normally closes said opening 31.

The chamber 25 has an opening through its bottom, the opening as disclosed being through the washer 30 and being designated 33 in Fig. 2, and said chamber 25 has a port 34 adjacent and within the confines of the thickened portion or web 16 and at the normal elevation of the spring valve 28, adapted to communicate with any one of the ports 17 in said thickened portion or web which may be selected. As shown in Fig. 2, the port 34 is completely covered by the 70 spring valve 28 when said spring valve is in its normal position, and the spring valve is of diameter to closely fit and nicely slide in the chamber 25.

The position of the axially rotatable cylinder in the cover 11 is insured by means of an annular shoulder 35 upon said cylinder and engaging the lower face of the cover cooperating with rotating lever 36 upon the portion of the cylinder extending beyond the 80 cover. The rotating lever is keyed to the cylinder as at 37 and includes a cavity 38 having a coil spring 39 and a ball 40 adapted to ride over the top of the cover or to enter any one of a series of depressions 41 therein. When the ball 40 rides into a depression 41, the cylinder position is fixed against accidental rotation. At this time the port 34 aligns with a port 17. A nut 42 having an opening 43 receiving the shaft 24 has threads 44 engaging threads 45 upon the upper end of the cylinder, above the rotating lever.

Clearly, turning the nut 42 down insures the fixed and rotatable relation of the cylinder in the cover.

The cross-section of the cylinder 20 which includes the spring-valve-receiving chamber 25 is of area to nicely fit the portion of the well or cavity 15 in which said chamber 25 is located, so that when the port 34 is aligned with a port 17 the adjacent ends of said 10 aligning ports are contiguous to provide tight passages from the measuring chamber to the bearings. A channel 46 at one side of the cylinder 20 and leading from the reservoir to the opening through the washer 30 is provided. At one of its positions, the port 34 communicates with this channel. Numeral 47 represents a drain plug at the base of the well or cavity 15.

The manner in which the lubricator pump 20 functions is obvious. Supposing that the reservoir contains lubricant and that the piston or plunger is at its lowest elevation, raising of the piston or plunger to the position of Fig. 2 draws or sucks lubricant into 25 the measuring chamber, the ball valve being lifted against gravity from the spring valve. Now when the piston or plunger has been elevated and the cylinder 20 has been rotated in the manner set forth to cause the 30 port 34 to align with a port 17 and the piston is then depressed, the first action is for the lubricant under pressure in the measuring chamber to depress the spring valve 28 until the port 34 is uncovered. Further 35 depression of the piston forces the lubricant out through the port 34 and a selected port 17 to a bearing or the like. As soon as the pressure upon the lubricant in the measuring chamber is sufficiently reduced, the coil 40 spring 29 acts to cause the spring valve to cover the port 34, the shoulder 27 serving as a stop limiting the upward movement of the spring valve. The cylinder 20 can now be rotated to align the port 34 with a different 45 port 17, and upon repeating the operations just described, a different bearing can be lubricated.

The spring valve 28 is constructed to preclude the passage of lubricant from the reservoir to the measuring chamber and vice versa, except through the opening having the ball valve, and, clearly, this opening only allows the flow of lubricant due to pressure change from the reservoir to the measuring 55 chamber. When the pressure in the measuring chamber is greater, the ball valve is tightly seated. Should it be desired to return lubricant from the measuring chamber to the reservoir, the port 34 could be positioned to 60 align with the channel 46. With this port so located, depression of the piston will force the lubricant out of the measuring chamber into the reservoir.

Attention is called to the fact that at the 65 time of the suction stroke of the piston or

plunger, the coil spring 29 is holding the spring valve 28 in position to cut off a port 17 aligning with the port 34 from both the chamber beneath the spring valve and the chamber above it. The spring valve is of 70 such dimensions that when seated against the stop 27 it closes the port 34 off from the chamber beneath the spring valve, and said lower chamber and port 34 are, therefore, never in communication, while the port 34 is 75 in communication with the measuring chamber only when there is sufficient pressure in said chamber to depress the spring valve to uncover said port 34. At this time the port 34 becomes an outlet leading from the measuring chamber. When a particular port 17 has been selected to be aligned with the port 34 and the cylinder 20 has been rotated to align said ports, engagement of the ball 40 in a depression 41 locks the port 34 and a port 80 17 against the possibility of accidental displacement from aligning position.

Upon each elevation of the piston or plunger the measuring chamber is filled, and upon depression the full load may be forced 85 to a selected bearing or the like.

Having thus fully described the invention, what I claim as new and desire to secure by Letters Patent is:

1. A lubricator pump comprising an axially rotatable cylinder, a well for lubricant, the lower portion of said cylinder being situated in said well, said cylinder having a measuring chamber and a spring-valve-receiving chamber and there being communication between said well and said spring-valve-receiving chamber, a spring valve within said last mentioned chamber and beneath the measuring chamber, there being a port in the wall of the cylinder adjacent said spring valve, means normally holding said spring valve to cut off said port from both chambers, a check valve upon said spring valve, a lubricant displacing device in said measuring chamber, connections having 100 ports communicating with bearings to be lubricated and adapted to communicate with the port in said cylinder, and means for rotating said cylinder to align its port with the port of a selected connection. 105

2. A lubricator pump comprising a lubricant reservoir having a well at its lower end, an axially rotatable cylinder having its lowermost portion situated in said well, said cylinder having a measuring chamber and a 110 spring-valve-receiving chamber and there being a connecting channel between said reservoir and said spring-valve-receiving chamber; a spring valve within said last mentioned chamber and beneath the measuring 115 chamber, there being a port in the wall of the cylinder adjacent said spring valve, means normally holding said spring valve to cut off said port from both chambers, a ball valve upon said spring valve and within said 120

measuring chamber, a piston in said measuring chamber, means for reciprocating the piston, connections having ports communicating with bearings to be lubricated and adapted to communicate with the port in said cylinder, and means for rotating said cylinder to align its port with the port of a selected connection, whereby when the piston is given a suction stroke in the measuring chamber lubricant is drawn from the reservoir into said measuring chamber, and when said piston is given a pressure stroke, said

spring valve is depressed to uncover the port of said cylinder adapted to communicate with any one of said connections. 15

3. The combination as specified in claim 1, wherein means is provided for locking the cylinder against accidental displacement in any one of the operative positions to which it may have been rotated. 20

Signed at Bridgeport, in the county of Fairfield, and State of Connecticut, this 26th day of November, A. D. 1924.

CARL F. JENSEN
